UNITED STATES PATENT OFFICE.

HENRY F. SCHMIDT, OF SWARTHMORE, PENNSYLVANIA, ASSIGNOR TO WESTINGHOUSE ELECTRIC AND MANUFACTURING COMPANY, A CORPORATION OF PENNSYLVANIA.

HOT-WELL EJECTOR.

Application filed October 22, 1920. Serial No. 418,820.

To all whom it may concern:

Be it known that I, HENRY F. SCHMIDT, a citizen of the United States, and a resident of Swarthmore, in the county of Delaware 5 and State of Pennsylvania, have invented a new and useful Improvement in Hot-Well Ejectors, of which the following is a specification.

My invention relates to ejectors and it 10 has particular relation to that type of ejector adapted to withdraw condensate from the hotwell of a condenser and to discharge it to a feed water heater or other receptacle at a substantially higher pressure.

An object of this invention is to provide 15 an ejector system for removing condensate from a condenser wherein the ejector shall be positive in starting and continuous in operation when a normal vacuum is held 20 within the condenser.

A further object of my invention is to provide an ejector system for removing condensate from a condenser, wherein the ejecting action of the condensate ejector will be 25 automatically reestablished should the condensate ejector fail to function by reason of abnormal condenser conditions.

A further object is to provide an overflow device for a hotwell ejector with an 30 auxiliary ejector, whereby the condensate will be returned to the condenser until a sufficient pressure is built up within the ejector to enable it to discharge the condensate at the required higher pressure.

I attain these objects by means of the 35 system shown in the accompanying drawing in which the figure shown is a diagrammatic illustration of the elements of my invention.

The vacuum maintained in the shell and 40 hotwell of a surface condenser is generally about 28 inches of mercury or the pressure existing therein about one pound absolute. The condensate is disposed of in any convenient manner, but is usually discharged 45 into a feed water heater, and as the pressure therein is substantially that of the atmosphere, some means must be employed to discharge the condensate against this higher pressure. This is commonly accomplished 50 by means of a hotwell ejector in which the steam, after expanding through the nozzle, acquires a high velocity and imparts its velocity energy to the condensate, and the

latter, passing through a velocity-pressure conversion device, has a sufficient amount of 55 its velocity energy changed into pressure energy so that it may discharge against the required pressure.

In order to evacuate a receptacle wherein 60 a relatively low pressure exists it is necessary to build up a considerable pressure in the ejecting device. For this reason, in the type of apparatus above mentioned, much difficulty has been experienced in starting 65 the ejector when a normal vacuum is held within the surface condenser. In accordance with this invention, I eliminate this difficulty by placing an overflow in the discharge conduit of the ejector, this overflow having 70 a communication with a receiving chamber of an auxiliary ejector. The auxiliary ejector is of the same general construction as the hotwell ejector and is preferably operated by an independent source of motive 75 fluid. An evacuating device of high efficiency and reliability is provided by the unique relation and joint action of the two ejectors shown in the drawing and referred to in the following specification.

Referring to the drawing for a more detailed understanding of my invention, I indicate a surface condenser at 10 which discharges condensate into a hotwell 11. The condensate is conducted from the hotwell 11 to a receiving chamber 12 which is associated therewith. A hotwell ejector 27 is preferably operated on exhaust steam from non-condensing auxiliaries, or in case of a deficiency from this source, on live steam, 90 supplied by a conduit 13. The steam is expanded through a nozzle 14 into a mixing chamber 15 where it combines and entrains the condensate from the hotwell 11, the resultant mixture being discharged through a 95 diffuser 16 into a discharge conduit 17 which in turn discharges into any desired receptacle, such as a feed water heater. The discharge conduit 17 is provided with a check valve 18 to prevent back flow into 100 the condenser.

The hotwell ejector is provided with an overflow 19 which communicates through a conduit 20 with the receiving chamber 21 of an auxiliary ejector 22. Steam from any independent source is supplied to the auxiliary ejector through a conduit 23. The

steam expands through a nozzle 24 into the mixing chamber 25 where it entrains the overflow from the hotwell ejector 27, the resultant mixture being discharged through a conduit 26 into the top portion of the surface condenser.

The operation of my device is as follows. Steam is admitted to the supply nozzle 14, thereby entraining the condensate in the receiving chamber 12 and delivering the same through the mixing chamber 15 into the diffuser 16 and attempting to discharge it through the conduit 17 to the feed-water heater or other receptacle which is normally at atmospheric pressure. When the ejector is started, however, there is an insufficient pressure within the diffuser 16 to discharge the condensate against the higher atmospheric pressure and the condensate collects in the overflow chamber 19 from whence it is conducted to the receiving chamber 21 of the auxiliary ejector 22. The auxiliary ejector, operated on an independent steam supply, injects the overflow condensate directly into the upper portion of the condenser, from whence it circulates back to the hotwell. This circulation of motive fluid and condensate continues until a sufficient pressure is built up within the ejector to discharge the condensate through the diffuser 16 and check valve 18 against atmospheric pressure, when the auxiliary ejector may be shut off.

It may be preferable, however, to provide a constant supply of low-pressure steam to the auxiliary ejector since the force of the jet in the main ejector may become insufficient under abnormal conditions of operation to discharge the condensate against existing back pressure into the condensate receiving means. Such a failure of the main ejector may be due to an insufficiency of water in the hotwell to produce a solid jet, a condition occasioned by the operation of the power plant at a light load. Another cause of failure of the main ejector may be the high temperature of the condensate, ejectors working under high vacuum condenser conditions being unable to handle water at a higher temperature than 160° F. In either case, the water or mixed water and steam, discharged by the main ejector is conveyed from the overflow chamber 19 to the receiving chamber 21 and returned by the auxiliary ejector to the condenser, from whence it falls again to the hotwell. This circulation through the hotwell, main and auxiliary ejectors, and condenser continues until, in one case, a sufficient amount of water has accumulated in the hotwell, the pressure built up in the main ejector and the discharge of condensate through the conduit 17 reestablished; or in the other case, until the temperature of the water has been reduced by repeated contact with the cooling sur-

faces of the condenser to such a temperature as will permit the main ejector to function normally.

The advantages incident to the employment of my improved ejector system are readily apparent from the above description. The construction eliminates the difficulties commonly experienced in the starting of a hotwell ejector by making provision for automatically starting the pumping action of the main ejector. Moreover, the automatic starting of the ejector may be accomplished under conditions of high vacuum in the condenser and of high temperature of the condensate, a condition under which the hotwell ejector ordinarily used in condenser installations cannot be started. It has the further advantage of being able to restart automatically the ejection of condensate when by reason of abnormal condenser conditions, the hotwell ejector has ceased to function. This obviates the necessity of constant attention on the part of an attendant and the danger of flooding and loss of vacuum within the condenser. My improved condensate ejecting mechanism possesses the further advantage of being simple and compact in structure and efficient to a high degree in operation.

While I have shown my invention in but one form, it will be obvious to those skilled in the art that it is not so limited but is susceptible of various other changes and modifications, without departing from the spirit thereof and I desire, therefore, that only such limitations shall be placed thereupon as are imposed by the prior art or as are specifically set forth in the appended claims.

What I claim is:

1. In combination with a condenser, a hotwell attached thereto, a condensate ejector adapted to withdraw condensate from the hotwell, an overflow device at the discharge of the ejector, and impelling means associated with the overflow device whereby the overflow condensate may be returned to the condenser.
2. In combination with a condenser, a hotwell, a condensate ejector adapted to withdraw condensate therefrom, an overflow device at the discharge of the ejector and an auxiliary ejector supplying communicating means between the overflow device of the condensate ejector and the condenser.
3. In combination with a condenser, a hotwell, a condensate ejector associated therewith comprising a supply nozzle, a receiving chamber and a mixing chamber, the condensate being entrained by the supply fluid in the receiving chamber and delivered to the mixing chamber, a diffuser, an overflow device between said mixing chamber and said diffuser and impelling means associated with the overflow device to return the overflow condensate to the top portion of the

condenser from which it is withdrawn, and a check valve at the discharge end of said diffuser.

4. In combination with a condenser having a hotwell associated therewith, a plurality of condensate ejectors, a first ejector having an overflow device connected thereto, said ejector communicating with the hotwell of the condenser, and a second ejector communicating with the overflow device of the first ejector and discharging overflow condensate through a conduit to the condenser.

5. In combination with a hotwell ejector for condensers, an overflow chamber therefor, and means for evacuating said overflow chamber.

6. In combination with a hotwell ejector for condensers, an overflow device associated therewith, and fluid actuated means for 20 evacuating said overflow device.

7. In combination with a hotwell ejector for condensers, an overflow device associated therewith, and impelling means for 25 evacuating said overflow device.

8. In combination with a hotwell ejector for condensers, an overflow device associated therewith, and fluid pressure means for 30 exhausting said overflow device to the condenser.

In testimony whereof, I have hereunto subscribed my name this 20th day of October, 1920.

HENRY F. SCHMIDT.
